UNITED STATES PATENT OFFICE.

CHARLES ADAM HARTMANN, OF WASHINGTON, DISTRICT OF COLUMBIA.

TEMPORARY BINDER.

SPECIFICATION forming part of Letters Patent No. 729,763, dated June 2, 1903.

Application filed September 12, 1902. Serial No. 123,118. (No model.)

To all whom it may concern:

Be it known that I, CHARLES ADAM HARTMANN, of the city of Washington, District of Columbia, have invented certain new and useful Improvements in Temporary Binders; and I do hereby declare the following to be a full, clear, and exact description of the invention, such as will enable others skilled in the art to which it appertains to make and use the same.

My invention relates to temporary binders for loose leaves or sheets, and has for its object to provide a simple and efficient mechanism for clamping or securing the leaves or sheets within the cover, which mechanism may be quickly released to permit leaves to be removed or inserted and the binder correspondingly contracted or expanded at will, and which mechanism may be operated to quickly release all of the leaves and permit the cover to be opened out flat or entirely removed.

The invention is illustrated in the accompanying drawings, in which—

Figure 1 is a perspective view of my temporary binder applied to secure together the several leaves or sheets of an account-book, the cover being partly broken away to show the construction of the parts. Fig. 2 is a transverse section through the binder, showing the several parts in locked relation. Fig. 3 is an enlarged perspective view showing the arrangement of the clamping-plates, the retaining-posts, and the locking-latch. Fig. 4 is a perspective view of the rear portion of a single loose sheet, showing the arrangement of the recesses which engage the posts in the binder. Fig. 5 is a longitudinal section through one of the retaining-posts, illustrating the construction whereby the same is adjusted.

Referring to the drawings, the numerals 11 represent the covers of the book or binder, which are preferably united by a back 1' to form an integral structure. It is desirable that the back should be quite flexible and of sufficient fullness to readily accommodate itself to varying thicknesses of leaves or sheets which are retained between the covers, and to this end the back is preferably constructed of flexible material of somewhat less thickness than the covers.

Secured to one end of the covers is a clamping-plate 3, which is preferably inclosed within the body of the cover. Securely attached to said cover, and preferably between the outer portion thereof and the plate 3, are two retaining-posts 4 4, each of which consists of a threaded socket 4', having a head 4² and a co-operating screw 5, having a flat head 5', said socket and screw constituting a longitudinally-adjustable post. Upon the other cover and in parallel relation to the plate 3 is mounted a second clamping-plate 6, which is provided with circular orifices 6' 6', registering with the posts 4 4 and of sufficient size to permit the heads 5' of the screws 5 to pass freely through them. Centrally disposed upon plate 6 and pivoted thereto by a suitable stud 7' is a locking-latch 7, provided with two oppositely-extending notches 7², which are adapted to embrace the shanks of the screws 5 5 under the heads thereof, thereby locking the covers securely upon the loose leaves or sheets forming the contents thereof.

In order to facilitate the insertion or removal of the sheets or leaves, I provide the latter with two recesses 2' 2' in their rear edges, which are preferably of uniform width and register with the posts 4 4 when in proper position for binding.

To apply the binder to its intended use, a number of loose sheets 2, provided with recesses 2' 2', are laid upon the lower cover in such a position that the posts 4 4 occupy the corresponding recesses in the sheets. The upper cover is then folded over parallel with the lower until the heads of the screws 5 5 pass through the openings in the upper cover and the plate 6. The latch 7 is then swung upon its pivot until the recesses in the end thereof engage the screws 5 5 under the heads thereof, after which the screws are turned down in their respective sockets until the leaves are clamped with sufficient pressure between the covers to insure their retention in the binder. Should it be found necessary to remove one or more leaves, the latch 7 is swung out of locking position and the upper cover thereby released, after which any of the leaves may be removed as desired, when the upper cover is again swung into place and the latch caused to engage the project-

ing heads of the screws 5 5. Should it be found necessary to add additional sheets to the book, it is only necessary to back the screws 5 5 out of the threaded sockets 4' 4' a 5 sufficient distance to accommodate the additional thickness of the leaves, after which the latch 7 is released, as before, the upper cover swung back, and the new leaves slipped into place, with their notches engaging the 10 posts.

It is to be particularly noted that in applying additional leaves to the book or removing leaves therefrom no lateral adjustment of the retaining-posts is necessary, as the recesses 2 in the back edges of the leaves pass freely over the posts at all times. Furthermore, in order to remove one or more leaves from the middle of the book it is not necessary to first remove all the leaves above the 15 one to be removed, as any leaf may be slipped from between its fellows as soon as the pressure on the cover is removed by swinging the latch 7 out of operative position. The particular form and character of the slots 2' 2', 20 in the loose leaves is of particular advantage in connection with binders of this character, as by their use any sheet of the desired size may be bound into the volume by cutting recesses at the proper points along one edge, 25 30 which may be accomplished by a simple cutting instrument, such as a knife or a pair of shears, and therefore does not require special perforating-tools, as is generally the case in binders heretofore in use, wherein the sheets 35 were provided with slots of varying cross-section.

It is to be noted that the binder, as above described, not only affords an efficient means for adjusting the covers to the size of the 40 contents, but also affords a particularly efficient retainer for loose sheets or leaves whose aggregate thickness is not variable, but which sheets or leaves are moved or shifted about among themselves. Under the 45 latter conditions the posts 4 4 need not be adjusted for length, but by simply releasing the latch 7 the clamping effect of the upper cover will be sufficiently reduced to permit any sheet or sheets to be slipped out of any 50 portion of the book and to be correspondingly inserted in any other portion as desired.

Having thus described my invention, what I claim is—

1. A temporary binder, comprising covers, 55 posts secured to one of said covers, and projected through the other cover, and a latch comprising a bar having notches in the opposite ends thereof pivoted to said latter cover

and engaging the projecting posts to lock the covers upon the contents thereof. 60

2. A temporary binder, comprising covers, longitudinally-adjusted posts secured to one of said covers and projecting through the other cover, and a latch comprising a bar having notches in the opposite ends thereof pivoted to said latter cover and engaging the projecting posts to lock the covers upon the contents thereof. 65

3. A temporary binder, comprising covers, adjustable posts secured to one of said covers 70 and projecting through the other cover, each of said posts comprising a threaded socket and a coöperating headed screw, and a latch comprising a bar having notches in the opposite ends thereof pivoted to said latter cover 75 and engaging the projecting posts to lock the covers upon the contents thereof.

4. The combination, with a number of leaves provided with recesses, of uniform cross-section of a temporary binder for said leaves, said binder comprising covers, posts engaging the recesses of the leaves, said posts being secured to one of said covers and projecting through the other cover, and a latch pivoted to said latter cover and engaging the 80 projecting posts to lock the covers upon the leaves. 85

5. The combination, with a number of leaves provided with recesses of uniform cross-section in one edge thereof, of a temporary binder for said leaves, said binder comprising covers, longitudinally-adjustable posts engaging the recesses in the leaves, said posts consisting of male and female screw-sections secured to one cover and projecting 90 through the other cover, and a latch pivoted to said latter cover and engaging the projecting posts to lock the covers upon the leaves. 95

6. The combination, with a number of leaves provided with recesses of uniform cross-section in one edge thereof, of a temporary binder for said leaves, said binder comprising covers, clamping-plates carried by each cover, longitudinally-adjustable posts secured to one of said clamping-plates and 100 projecting through the other plate and the corresponding cover, a latch pivoted to said latter plate and engaging the projecting posts to lock the covers on the leaves. 105

In testimony whereof I affix my signature in presence of two witnesses.

CHARLES ADAM HARTMANN.
